UNITED STATES PATENT OFFICE.

JOHN STORK, OF SAN DIEGO, CALIFORNIA.

MEASURING DEVICE.

Application filed April 29, 1926. Serial No. 105,539.

My invention relates to and has for its purpose the provision of a measuring device which embodies the combination of a tape measure and an extensible rule structure in such manner that the rule structure is used as a support to sustain the tape measure in any selected length and in linear form, whereby a correct measuring and reading can be conveniently and quickly secured.

I will describe only one form of measuring device embodying my invention and will then point out the novel features thereof in claims.

In the accompanying drawings,

Figure 1 is a view showing in side elevation one form of measuring device embodying my invention in partly extended position;

Figure 2 is a view showing in top plan the measuring device in folded position;

Figure 3 is a longitudinal sectional view taken on the line 3—3 of Figure 2.

Figure 4 is a fragmentary sectional view showing the confronting ends of two tape supporting sections of the device and the corresponding latch.

Referring specifically to the drawings, my invention, in its present embodiment, comprises a substantially U-shaped frame constructed of two sheets of metal or other suitable material 15 and 16 having flanges 17 and 18, respectively, bent to have interlocking engagement and to form a right angle projection for a purpose to be herein-after explained. Within the frame is arranged a casing 19 having a spring wound drum 20 on which a steel measuring tape 21 is wound and normally held in coiled form by the action of the spring. The casing is formed with a slot 22 through which a portion of the tape is at all times extended.

For supporting the steel tape in linear form and in any selected length, I utilize the conventional structure of an extensible rule. This structure is here termed an extensible support and comprises a plurality of linear sections 23 formed of wood or other suitable material superimposed when in folded position as shown in Figure 3, and interlatched at their ends by latching devices 24. The lowermost section is permanently secured within the frame by screws or rivets 25, but the other sections are extensible one upon the other and slidably connected by brackets 26. When any one section is in

fully extended position with respect to an adjacent section, the latching devices function to releasably lock the first section in fully extended position. The latching devices are of the conventional type used in extensible rulers as illustrated in Figure 4 to permit sliding of one section upon the other and to latch a section in fully extended position on an adjacent section. To release the device in folding a section upon another it is only necessary to depress a latching finger 24^a when the section can be slid inwardly on an adjacent section.

The uppermost section 23 has secured to its outer end the free end of the tape 21 by means of a screw or other fastening member 27. To maintain the tape in operative engagement with the supporting sections as they are moved to extended position, I provide a plurality of brackets 28 having slots 29 through which the tape 21 extends, in a manner to prevent sagging of the tape and to thus hold it in line. By reference to Figure 3, it will be seen that the several brackets 28 are graduated in length, with the uppermost bracket secured to the inner end of that section 23 which is third from the topmost section, while the remaining brackets are secured to every other section 23.

In order to effect a correct reading, the tape 21 is adapted to be engaged by a clamping finger 30 secured to a pindle 31 journaled in the parallel portions 15 and 16 and carrying at its outer end an arm 32 disposed exteriorly of the frame and manually operable to move the finger 30 against a cross bar 33 secured in the frame so that the tape will be pressed against the cross bar and a reading made on the tape at that point intersected by the forward edge of the cross bar.

In practice, the supporting sections 23 can be successively extended from the frame by pulling outwardly upon the sections and thereby unwinding the tape 21 with the latter sliding through the openings 29 of the brackets. In measuring the openings of buildings for screens, or in any other use, the device is placed in the opening with the frame projections 17 and 18 in contact with one wall of the opening. The supporting sections may now be extended until the right hand end of the topmost section contacts with the opposite wall of the opening when the distance between the two walls can be accurately determined by the reading given upon the tape 21 at the point where the for-

ward edge of the cross bar 33 intersects the tape. It is to be particularly noted that the free end of the tape 21 begins with a reading of $3\frac{1}{2}$ inches, in order to compensate for the distance between the forward edge of the cross bar 33 and the left hand vertical edge of the frame projections 17 and 18; thus the reading at the forward edge of the cross bar will be correct.

- 10 10. It will be understood that in order to restore the supporting sections to folded position, as shown in Figure 3, it will be necessary to first release the latching devices 24 for each of the sections, and when moving 15 the sections to folded position the spring drum automatically rewinds the tape within the casing 19.

My invention, although employing the structure of a conventional extensible rule, 20 possesses the important advantage of accurately measuring distances of or between objects in contradistinction to the ordinary extensible rule. This is due to the fact that it is unnecessary to fully extend each and every 25 section, as is necessary with the conventional rule, in order to secure an accurate measurement, because the measuring tape determines the reading and not the figures upon the sections of the rule, it being noted that I have 30 omitted from the supporting sections the measuring numerals.

Although I have herein shown and described only one form of measuring device embodying my invention, it is to be understood that various changes and modifications 35 may be made therein without departing from the spirit of the invention and the spirit and scope of the appended claims.

I claim as my invention:

- 40 1. A measuring device comprising a frame, a plurality of supporting sections extensibly associated with each other and with one of the sections secured to the frame, a measuring tape supported in roll form within the 45 frame, and brackets secured to certain of the supporting sections and having registering openings through which said tape is slidably extended, the outer end of the tape being secured to one of the supporting sections so 50 as to move with said section as the latter is extended or folded.
- 55 2. A measuring device comprising a frame, a plurality of supporting sections extensibly associated with each other and with one of the sections secured to the frame, a measuring tape supported in roll form within the

frame, brackets secured to certain of the supporting sections and having registering openings through which said tape is slidably extended, the outer end of the tape being secured to one of the supporting sections so as to move with said section as the latter is extended or folded, a cross bar carried by the frame, and a clamping finger movable to compress the tape into engagement with the 60 cross bar for the purpose described.

3. A measuring device as embodied in claim 2 wherein said frame comprises two plates having interlocking flanges to provide a projection at one end of the frame.

4. A measuring device comprising a frame, a plurality of supporting sections extensibly associated with each other and with one of the sections secured to the frame, a measuring tape supported in roll form within the 75 frame, and brackets secured to certain of the supporting sections and having registering openings through which said tape is slidably extended, one end of the tape being secured to one of the supporting sections so as to move with said section as the latter is extended or folded, said frame including two 80 flanges having interlocking engagement and providing a projection at one end of the frame.

5. A measuring device comprising a tape arranged in roll form, means acting to maintain the tape in roll form, an extensible structure of rigid sections to which the tape is connected so that the tape is extended in linear form as the structure is extended, and against the action of said means, a bar on said extensible structure, and means movable to cause the tape to engage the bar for the 85 purpose described.

6. A measuring device comprising a frame, a plurality of rigid supporting sections extensible linearly one upon the other and comprising end sections and intermediate sections with one of the end sections secured 100 to the frame, a measuring tape supported in roll form in the frame, one end of the tape being secured to the other of the end sections so as to move therewith as the sections are extended or folded to accordingly unwind or wind the tape, and means secured to the intermediate sections slidably associated with the tape for causing the latter to be supported in linear form when the sections are extended.

JOHN STORK.
